UNITED STATES PATENT OFFICE.

CHARLES R. BARR, OF PHILADELPHIA, PENNSYLVANIA.

COMBINED ROLLER AND ICE SKATE.

1,187,961.

Specification of Letters Patent. Patented June 20, 1916.

Application filed June 7, 1915. Serial No. 32,564.

To all whom it may concern:

Be it known that I, CHARLES R. BARR, a citizen of the United States, residing in the city and county of Philadelphia, State of Pennsylvania, have invented a new and useful Combined Roller and Ice Skate, of which the following is a specification.

My present invention consists of a novel construction of a combined ice and roller skate which may be readily converted from one type of a skate to the other.

It further consists of a novel construction and arrangement of a base plate adapted to receive an ice runner or blade or to receive the rollers, said runner and rollers being keyed in a novel manner with respect to the base plate.

Other novel features of construction and advantage will hereinafter more clearly appear in the detailed description of my invention.

For the purpose of illustrating my invention, I have shown herein a typical embodiment thereof which, in practice, will give satisfactory and reliable results, although it is, of course, to be understood that the various instrumentalities of which my invention consists may be variously arranged and organized and that my invention is not limited to the precise arrangement and organization of these instrumentalities as herein set forth.

Figure 1 represents a sectional elevation of a combined ice and roller skate embodying my invention. Fig. 2 represents a sectional elevation on line $\alpha-\alpha$ of Fig. 1. Fig. 3 represents a sectional plan view on line $y-y$ of Fig. 4. Fig. 4 represents a side elevation of the skate as the same appears when provided with an ice runner. Fig. 5 represents a section on line $z-z$ of Fig. 4, showing the blade in detached position.

Similar numerals of reference indicate corresponding parts.

Referring to the drawings:—1 designates a sectional base plate or foot receiving portion which is made in overlapping sections so that the parts may be readily adjusted with respect to each other, and said sections are slotted or apertured to provide for the longitudinal adjustment.

2 designates a fastening device, a desired number of which I employ in order to fix the parts in their assembled position, one of said fastening devices being adjustable.

Any desired means may be employed for

securing the base plate with respect to the shoe of the user, and I have therefore illustrated the conventional type of fastening means, which needs no description to those skilled in this art. The base plate 1 is provided at the heel portion with the downwardly deflected clip 3, the lower portions of which are substantially parallelly arranged and are adapted to receive the roller or blade supporting means. At the forward portion of the base plate is secured a clip 4 which is constructed in a similar manner to the clip 3 and connected to the base plate preferably by riveting the same thereto.

5 designates a support, which is secured within the clip 3 in any desired manner and this support 5 is provided with a wedge-shaped slot, the side walls of which converge toward the rear end of the skate.

7 designates a front support having a wedge-shaped keyway or slot 8 which is adapted to receive a wedge-shaped key 9 carried by a block 10 having the downwardly extending flanges 11 and 12, respectively, which are apertured to receive a pin or rod 13.

14 designates a spring clip comprising a plate of spring metal having the ends thereof downwardly deflected and engaging the sides of a cushion 15 of resilient material which is carried by the axle supporting bracket 16. The bracket 16 has slots 17 opening through its upper portion in which the pin or rod 13 is located. The bracket 16 is formed from an integral piece of material which is bent around and connected with the axle 19 in any desired manner and is then bent upwardly at the ends to form a chamber to receive the resilient cushion 15.

18 designates rollers which are preferably mounted in anti-friction devices on the axis 19. The rear support 7 is constructed in a similar manner to the construction seen in Fig. 2, except that the slot therein preferably has its side walls converging rearwardly, as seen in Fig. 3. The supports 7 and 5 are connected with respect to the clips 4 and 3, respectively, by means of fastening devices 20, (see Fig. 2). These fastening devices preferably extend into their respective supports, in order to contact with the wedge-shaped key of the roller support to lock the same in adjusted position.

When it is desired to substitute a runner or blade for the rollers, a runner 21 of novel

construction is employed, which is provided at its rear end with a wedge-shaped key or tongue 22, the side walls of which are also converging and this convergence is toward 5 the end of the skate, so that the forward stroke will tend to wedge the key or tongue 22 in the slot 6. The front portion of the runner 21 is provided with a wedge-shaped key 23, the shape of which corresponds to 10 the shape of the key 9, so that it will slide into the keyway 8 and be locked in position by means of the fastening devices 20.

It will be apparent from the foregoing 15 that I have devised a convertible ice and roller skate which may be readily converted from one type of a skate to the other by the user, and that I employ a simple and compact construction which may be cheaply manufactured and which is not liable to get 20 out of order or interfere with the skating operation.

It will now be apparent that I have devised a novel and useful combined roller and ice skate, which embodies the features of 25 advantage enumerated as desirable in the statement of the invention and the above description, and while I have, in the present instance, shown and described a preferred embodiment thereof which will give in 30 practice satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. A convertible ice or roller skate, comprising a sectional base plate, means to se- 40

cure said sections in their adjusted positions, said sections each having a clip extending downwardly therefrom, a support secured within each clip and provided with a longitudinally extending wedge-shaped slot, a 45 tread member having keys engaged in said slots, and fastening devices passing laterally through said clips and supports and contacting with said tread member.

2. A convertible ice or roller skate, comprising a sectional base plate, means to longitudinally adjust said sections, a downwardly extending clip carried by the rear section, and having parallelly arranged walls, a support having a slot at its bottom and engaging 50 said parallelly arranged walls, a second clip depending from the forward portion of said base plate and having parallelly arranged walls, a support engaging the walls of said second clip and having a slot therein, 55 a tread member having means to engage said slots, and fastening devices engaging said first clip and its support, and the means carried by the tread member.

3. A convertible ice or roller skate, comprising a base plate, having a front clip and a rear clip, a front support carried by the front clip, a rear support carried by the rear clip, blocks having means to engage said support, a pin passing through each block, 70 a bracket having slots to receive said pin, a cushion carried by said bracket and located beneath said pin, a spring passing over said pin and engaging said cushion, an axle carried by said bracket, and rollers mounted on 75 said axle.
